UNITED STATES PATENT OFFICE.

HANS J. WINTHERLICH, OF OMAHA, NEBRASKA, ASSIGNOR OF ONE-HALF TO
RICHARD H. LARSON, OF OMAHA, NEBRASKA.

MILK-STERILIZING JAR-CLOSURE.

1,383,894.

Specification of Letters Patent.

Patented July 5, 1921.

Application filed July 30, 1920. Serial No. 399,977.

To all whom it may concern:

Be it known that I, HANS J. WINTHERLICH, a citizen of the United States, residing at Omaha, in the county of Douglas and State 5 of Nebraska, have invented new and useful Improvements in Milk-Sterilizing Jar-Closures, of which the following is a specification.

The object of my present invention is the 10 provision of a hermetical jar closure calculated to readily lend itself to the thorough sterilization of milk in the home.

To the attainment of the foregoing the invention consists in the improvement as 15 hereinafter described and definitely claimed.

In the accompanying drawings, hereby made a part hereof:

Figure 1 is a diametrical section showing 20 my novel closure as arranged in the mouth of a jar.

Fig. 2 is a similar view taken at an angle to Fig. 1.

Fig. 3 is a plan view of the closure with 25 the parts in the same positions as in Fig. 1.

Similar numerals of reference designate 30 corresponding parts in all of the views of the drawings.

The jar 1 is provided in the inner wall of 35 its mouth with a groove 2, and in the preferred embodiment of my invention the closure comprises a cover member 3, a disk 4 arranged below and spaced from the cover 3, and a socket member 5, the latter being open at its upper end and closed at its lower 40 end. The cover 3 is provided with a pair of reversely inclined curvilinear cams 6 which are preferably struck up from the cover as illustrated. The said cover is also provided with an upstanding marginal flange 7, and a flange 8 that reaches outwardly from the upper edge of the flange 7 and is designed to rest on the edge around the jar mouth as shown. The disk 4 is of 45 concavo-convex form in the cross section and is therefore possessed of expanding capacity. At its periphery the said disk 4 is provided with a depending flange 9 which is merged into an outwardly extending flange 10. Surrounding the inner portions of the 50 cover 3 and disk 4 is a gasket 11, preferably of rubber. The said gasket is arranged in the mouth of the jar and is interposed between the flange 8 of the cover 3 and the flange 10 of the disk 4. Consequently when 55 the cover 3 is crowded downwardly the gas-

ket 11 will be compressed after the manner shown in Fig. 2 with the result that the mouth of the jar will be hermetically sealed.

As clearly shown the socket member 5 is provided at its outer end with a head 12, 60 and at an intermediate point of its length with an exterior rib or flange 13. The disk 4 snugly surrounds the socket member 5 above the rib 13, and also snugly surrounding and capable of being turned about the 65 socket member 5 is a locking member 14 which is designed to be moved on the reversely arranged cams 8 with a view to placing the disk 4 under tension as shown in Fig. 2 and thereby compressing the gasket 70 11 for the purpose before described. It will also be noted that the locking member 14 is arranged below the head 12 of the socket member 5, and that said locking member 14 is provided with upstanding finger portions 75 15.

It will be apparent from the foregoing that by turning the locking member 14 in one direction the operator is enabled to secure the closure in the jar mouth and at the 80 same time hermetically seal the jar, while by turning the locking member 14 in the opposite direction the closure is rendered loose, and may then be readily removed from the jar. As before indicated my improvement 85 is designed especially to lend itself to the sterilization of the jar contents in the home, and in this connection it will be understood that with milk in the jar, and the jar hermetically sealed as described it is simply 90 necessary for the housewife to place the jar on a foraminous false bottom of a pail filled with water and to place the pail over a fire, after which a thermometer is displayed in the socket member 5. Then when the thermometer indicates a temperature of between 150° and 160° F., the pail is removed from the fire. The jar however, is left in the water in the pail for 25 minutes, after which the pail is arranged under a water spout, 100 and cold water is permitted to run into the pail until the water is quite cold and the milk is of the same temperature as the water. Manifestly in this way the contents of the jar may be conveniently sterilized, and it 105 will be appreciated that my improvement contributes materially to the convenience with which the sterilization process may be carried out.

Having described my invention, what I 110

claim and desire to secure by Letters-Patent, is:-

1. A jar closure comprising a cover member having reversely arranged cam portions 5 and also having a central aperture, a concavo-convex disk disposed below the cover member and having a central aperture, an annular gasket interposed between the cover member and the disk and surrounding portions of the same, a tubular socket member closed at its lower end and open at its upper end and arranged in the apertures of the cover member and the disk and having a head at its upper end and an exterior flange 10 at an intermediate point of its length, the head being disposed above the cover member and the flange below the disk, and a locking member revoluble about the socket member below the head thereof and above the 15 cam portions of the cover member.
2. A jar closure comprising a central

socket member closed at its lower end and open at its upper end, sealing members associated with and surrounding the socket member, and a locking member mounted 25 on and capable of being turned about the socket member to adjust the sealing members.

3. A jar closure comprising a socket member closed at its lower end and open at its 30 upper end and having abutments, a cover member surrounding the socket member, a disk surrounding the socket member and arranged above the lower abutment thereof, a locking member surrounding the socket 35 member and interposed between the upper abutment thereof and the cover member, and packing surrounding portions of the cover member and the disk and interposed between said cover member and disk. 40

In testimony whereof I affix my signature.

HANS J. WINTHERLICH.
